3996X

D.Pool,

Cracker Machine,

Patented Dec. 24, 1824.

Daniel Poole

3996X

The schedule referred to in these Letters Patent and making part of the same containing a description in the words of the said Daniel Poole himself of his improvement in the Machine for rolling and cutting crackers.

The first consists of a frame standing on four posts, the frame may be about six feet long, and the width agreeable to the number of cutters should be put in the machine, the height from three to four feet, the posts at one end of the machine which is called the head, extend ^{up} from two to three feet above the sides of said frame, where the slide works, in that the cutters are attached to, these posts are on a pitch of about fifteen degrees, there are two rollers being in two short posts back of the other head posts, one roller above the other which roll the dough, this dough is brought ^{thence} by an engine, gets its motion by means of two small rollers, one of them let into the sides close to the rollers that roll the dough, and the other at the back end, this engine is about four feet long and receives its motion from the rollers that roll the dough by means of bands and small pulleys, the dough passes through the rollers on a platform of lead where the cutters cut the crackers, this platform of lead is level with the lower roller that rolls the dough, there is another engine that takes these crackers from this platform which is about three feet long and is carried by rollers, the same as the other engine and gets its motion from the rollers that roll the dough on the same way as the other engine, the cutters are put on a plate

plate, which looks similar to a large goliath which works up and down in these mills. At the head, the cutters get their motion from a shaft which passes thru' under the platform with the beams at each end & fastened to connect the crank and slide together. The rollers get their motion from this platform by placing two pulleys upon at each end of the upper roller that holds the dough with pegs on them and bands round them, which must be loose and a catch in one side of the bands which catch in these pegs. There is a handle in one side of these bands which runs out to the platform and is connected to some cord when the cutters raise it gives motion to the rollers and when the cutters go down the rollers stand still; these cutters may be put on bread or any other metallic substance in one two or three rows together in any number from one to fifty or more.

The punches for these cutters are screwed in through the plate any number may be put in, there are small plates put in for clearers and get their motion by having two small wires riveted in each side of the plate and passes thru' the plate that the cutters are placed into which is fixed in by small handles, this each end when the cutters go down gives the motion to cut and draw the clearers up in the cutters, and when the cutters raise, the clearers are drawn out by means of a spring and clear the spaces pulled out. This handle is put in the center of the cutters and it goes up through the plate & small bars on the top $8\frac{1}{2}$ per side, this handle has no motion but is put in for the adjustment.
